UNITED STATES PATENT OFFICE.

JOHN B. SHEEHAN, OF ATCHISON, KANSAS.

HERNIAL TRUSS.

SPECIFICATION forming part of Letters Patent No. 733,879, dated July 14, 1903.

Application filed September 2, 1902. Serial No. 121,794. (No model.)

To all whom it may concern:

Be it known that I, JOHN B. SHEEHAN, a citizen of the United States, residing at Atchison, in the county of Atchison and State of 5 Kansas, have invented certain new and useful Improvements in Hernia-Trusses, of which the following is a specification.

This invention relates to trusses, and has special reference to that type of trusses designed for use in the treatment of hernia or rupture.

To this end the invention primarily contemplates a simple and practical form of truss which can be worn with perfect ease and comfort by the wearer, while at the same time providing effectual means for positively and firmly holding the afflicted parts in a natural position without danger of enlargement of the break or rupture. In the accomplishment of 15 these desirable objects the invention has in view a truss in which the parts are so constructed and arranged as to permit the truss to freely adjust itself to the movements of the body and at the same time always exert 20 a pressure directly on and over the hernia. In other words, the invention contemplates a truss which will remain in position under all conditions, is easily applied, and cannot possibly pinch the body.

With these and many other objects in view, which will more readily appear as the nature of the invention is better understood, the same consists in the novel construction, combination, and arrangement of parts herein- 35 after more fully described, illustrated, and claimed.

The essential feature of the invention involved in the novel mounting of the front and back pads is necessarily susceptible to 40 modification from a structural standpoint; but a preferred embodiment of the invention is shown in the accompanying drawings, in which—

Figure 1 is a perspective view of a single 45 form of truss designed for hernia of the right side, said truss being constructed in accordance with the present invention. Fig. 2 is an enlarged elevation of the front pad and the contiguous portion of the body-spring. 50 Fig. 3 is a detail sectional view on the line 33 of Fig. 2. Fig. 4 is an elevation of the back pad and the contiguous portion of the body

spring or band. Fig. 5 is a sectional view on the line 55 of Fig. 4.

Like numerals of reference designate corresponding parts in the several figures of the drawings.

In carrying out the invention the truss may obviously be made for either right or left hernia and also used as a double truss for a 60 double hernia; but for illustrative purposes it has been deemed sufficient to simply show in the drawings a single form of truss. Referring particularly to this truss, the numeral 1 designates the bowed body-band of an approximately semicircular form and preferably constructed of spring-wire in order to constitute the pressure-spring of the truss, and said pressure-spring or body-band is of a sufficient length to extend around the hip 70 of the wearer, with the opposite terminals thereof disposed respectively at the front and back of the body. The said pressure-spring or body-band 1 is provided at its front extremity with a downwardly-deflected supporting-terminal 2, which may be either a 75 separate part or integrally formed with the body-band, as shown in the drawings, but necessarily a rigid part thereof. The downwardly-deflected supporting-terminal 2 at the 80 front end of the body-band is preferably disposed at an obtuse angle to the adjacent portion of the band in order to provide an axis of movement for the front pad 3 substantially in line with the disposition of the tract 85 in which the hernia or rupture is located. The said front pad 3 may be formed of any of the materials of which truss-pads are ordinarily constructed; but in the present invention the said pad preferably consists of a 90 circular block provided with a flat inner face 4 and of a downwardly-tapering thickness, as plainly shown in the drawings, whereby the pad-body is thicker at the top than at the bottom, thus giving the pad the proper lift, 95 so that the parts will be held in position under all conditions without irritation of the body. By reason of the flat inner face of the pad the hernia will be held in natural position without any tendency to enlarge or keep 100 open the break or rupture, which is a very desirable thing in the treatment of this affliction. The said front pad 3 is provided on the outer or front side thereof with a socket-

plate 5, secured in place by screws or other equivalent fastening 6 and provided at the upper end thereof contiguous to the upper edge of the pad with an enlargement 7, in 5 which is formed a bearing-socket 8. The said bearing-socket 8 has swiveled therein the downwardly-deflected front terminal 2 of the body-band, thus completing a swivel-joint connection between the body-band and 10 the front pad, whereby the latter will be laterally tiltable on an approximately vertical axis, but will have no movement in any other direction. A swiveled connection between the terminal 2 and the socket 8 of the pad 3 15 is preferably provided by a screw-threaded engagement of the parts, which screw-threaded engagement not only permits of a free swiveled movement, but also provides for an adjustment with reference to its support. 20 The same character of swiveled connection is preferably employed in the mounting of the back pad, to be presently referred to. In addition to the slight lateral obliquity of the terminal 2 the same is slightly inclined inwardly to give a corresponding inward inclination to the front pad 3 in order that the latter may be perfectly adapted to the shape 25 of the body at the point of application. At its rear end the body-band 1 is provided 30 with a straight or approximately horizontal supporting-terminal 9, which is swiveled inside of the horizontally-disposed bearing-socket 10, formed in an enlargement 11 on the socket-plate 12, screwed or otherwise suitably 35 fastened to the outer side of the rear or back pad 13. The back pad 13 is also preferably of a circular form and is provided with a flat inner face 14 for contact with the body. The construction described provides for mounting 40 the back pad in such a way that the same is vertically tiltable on an approximately horizontal axis.

The socket-plates of the front and rear pads

are preferably provided with the offstanding holding-studs 15 and 16, which are engaged by a securing-strap 17, which is designed to loosely extend around the side of the body opposite the body-band 1 to guard against displacement of the truss.

From the foregoing it is thought that the 50 construction, self-adjusting action, and many advantages of the herein-described truss will be readily apparent without further description, and it will be understood that various changes in the form, proportion, and arrangement of parts may be resorted to without departing from the spirit or sacrificing any of the advantages of the invention.

Having thus described my invention, what I claim as new, and desire to secure by Letters 60 Patent, is—

In a truss, the body-band provided at its front end with a downwardly-deflected supporting-terminal, a front pad having a socket-plate provided with a socket enlargement 65 having a bearing-socket receiving said deflected supporting-terminal, both the latter and the bearing-socket having a screw-threaded engagement to provide both a swiveled connection and also for an adjustable mounting of the front pad, and a back pad having a socket-plate provided with a socket enlargement having a bearing-socket receiving the rear terminal of the body-band, said rear terminal of the body-band and also the bearing-70 socket carried by the back pad having a screw-threaded engagement to provide a swiveled connection and also for the detachable mounting of the back pad.

In testimony whereof I affix my signature 80 in presence of two witnesses.

JOHN B. SHEEHAN.
